(57) **CLAIM**

The ornamental design for a liquid container, as shown and described.

DESCRIPTION

FIG. 1 is a front perspective view of a bottle showing our new design.

FIG. 2 is a front elevation view of the bottle, which is axisymmetric in form, the finish as shown in the cross-hatched box is not a part of the design.

FIG. 3 is a top plan view thereof; and,

FIG. 4 is a bottom plan view thereof.
